UNITED STATES PATENT OFFICE.

BYERS W. KADEL, OF BALTIMORE, MARYLAND, ASSIGNOR TO THE T. H. SYMINGTON COMPANY, OF NEW YORK, N. Y., A CORPORATION OF DELAWARE.

DRAFT YOKE.

Application filed August 2, 1922. Serial No. 579,265.

To all whom it may concern:

Be it known that I, BYERS W. KADEL, a citizen of the United States, residing at Baltimore, in the State of Maryland, have 5 invented certain new and useful Improvements in Draft Yokes; and I do hereby declare the following to be a full, clear, and exact description of the invention, such as will enable others skilled in the art to which 10 it appertains to make and use the same.

My invention relates to the construction of draft yokes for railway cars and is designed to afford a device of this character which is especially well suited for co-operation 15 with a back-stop member positioned between the draft sills of the car at the rear of the draft rigging.

The principal object of the invention is to produce a strong and comparatively light 20 yoke which may be manufactured from cast steel without substantial liability of containing shrinkage cracks or similar defects due to improper distribution of the masses of metal. A further object of the invention 25 is to produce a draft yoke in which the metal is disposed in a manner enabling it efficiently to resist the shocks and strains to which the device is subjected in service.

A principal feature of the invention, generally 30 stated, consists in forming the yoke with parallel arms which are integrally united at their rear ends by transversely extending connecting means whose forward face is adapted to engage the cushioning unit of the draft rigging, and in extending the yoke arms in straight lines for a substantial 35 distance rearwardly of the said face by which the cushioning unit is engaged. A further primary feature of the invention 40 consists in connecting the arms of the yoke at their rear ends by means of a plurality of spaced webs one of which is adapted to engage a draft rigging back-stop and one of which is adapted to engage the cushioning unit of the draft gear, the said spaced webs being themselves connected by a plurality of parallel webs disposed in transverse alignment with the yoke arms. A still further feature of the invention involves integrally 45 connecting the arms of the yoke at their rear ends by means of a plurality of spaced webs one of which is adapted to engage a draft rigging back-stop and one of which is designed to engage the cushioning unit of the draft gear, the spaced webs being rigidly

united by a plurality of rearwardly divergent webs or flanges.

Other features of the invention, residing in particular relations of parts and in special structural details, will hereinafter appear 60 and be pointed out in the claims.

In the drawings illustrating the invention, the scope whereof is pointed out in the claims,—

Figure 1 is a view, partly in plan and 65 partly in horizontal section, of a draft yoke embodying the invention.

Figure 2 is a vertical longitudinal section of the construction shown in Fig. 1.

Figure 3 is a section on the line 3—3, 70 Fig. 1.

Figure 4 is a rear end elevation of the draft yoke.

Figure 5 is a side elevation of the rear end 75 portion of the yoke.

The invention is illustrated as embodied in a draft yoke of the so-called horizontal type, that is to say, a form of yoke having parallel arms 1 disposed opposite each other in horizontal alinement. These arms, 80 which, as is well known, are adapted to receive the cushioning unit of a draft rigging between them, are provided at their forward ends with suitable means for forming an operative connection with a car coupler. 85

In the form of yoke shown in the drawings each arm 1 is provided near its forward end with a longitudinally extending slot 2 for receiving a key adapted to pass through the slotted butt of the car coupler; and at the 90 forward ends of said slots the yoke arms are furnished with thickened portions 3 affording extended bearing area for the coupler connecting key when the device is subjected to draft strains. The arms of the 95 yoke are also shown as provided with transversely alined key slots 4 located somewhat to the rear of the slots 2. These slots 4 are for the purpose of receiving a key adapted to pass through a slotted follower block 100 located between the yoke arms in a well known manner at the rear end of the coupler. While, as will be appreciated by those skilled in the railway draft rigging art, the construction of the forward ends of the 105 yoke arms illustrated in the drawings is specifically designed to enable the yoke to form a part of what is generally designated as the Farlow two-key draft gear, the specific form of the forward end of the yoke forms 110

no part of the present invention and is not a limitation thereof.

The yoke arms 1 are integrally united at their rear ends by a plurality of spaced webs 5 and 6, respectively. The forward web 5 is adapted to engage the rear end of any well known or suitable cushioning unit; and the rear web 6 is adapted to engage and cooperate with a draft rigging back-stop. 10 The back-stop engaging face of the web 6 is preferably substantially the same width as the opening or space between the yoke arms 1.

The webs 5 and 6 are integrally connected by a plurality of parallel webs 7, preferably three in number, which are in transverse alignment with the yoke arms and are adapted to transmit directly to the web 6 the strains transmitted by the cushioning 20 unit of the draft rigging to the central portion of the forward web 5. The spaced webs 5 and 6 also are preferably integrally connected by a plurality of rearwardly divergent webs 8 and 9, 9, respectively, extending 25 perpendicular to the webs 7 and formed integral therewith. To afford increased bearing area for the rear end of the cushioning unit of the draft gear the web 5 may be conveniently extended outwardly on opposite sides of the yoke arms, as indicated at 10, 10, and for the purpose of bracing such extensions the divergent webs 8 and 9 are preferably also continued beyond the yoke arms 1, as well shown in 30 Figs. 2, 4 and 5. The portions of the divergent flanges on opposite sides of the yoke arms form tapering braces supporting the extensions 10 of the forward transverse web 5 against draft and buffing shocks imparted thereto in service.

The arms 1 are preferably continued in straight lines for some distance to the rear of the forward face of the web 5, as at 11, thus avoiding foul stresses at these places; 45 and also for the purpose of virtually separating the stresses communicated to the cushioning unit engaging web 5 from those of the yoke arms 1, the sections of metal 12 connecting the ends of the said web 5 to the 50 adjacent portions of the yoke are comparatively light, thus in effect practically preventing the transmission of substantial stresses between the yoke arms and the web 5 at these points.

55 The yoke strap metal forming the arms 1 in effect continues around through the rear end of the yoke, as indicated at 13 and 14, so that the connected webs 5, 6, 7, 8 and 9 practically constitute a framework that is 60 cast upon a continuous yoke strap.

Near their rear ends the yoke arms 1 are formed with outwardly projecting longitudinal ribs 15 which extend on opposite sides of the junctions of the transverse web 65 5 with the respective yoke arms 1. These

ribs, which may extend rearwardly to or substantially to the web 6 and which are preferably tapered at their ends, as indicated at 16 and 17, not only serve to center the yoke within the draft gear pocket or space 70 of the car, but also by reducing the effect of a quick change in the sections of metal at the junctions of the arms 1 of the yoke with the webs 5 and 6, minimize the crystallization of the material and the formation 75 of shrinkage cracks.

I claim:—

1. A draft yoke adapted at its forward end to be connected to a car coupler and having a rear end adapted to engage a draft rigging back-stop, said yoke involving a pair of spaced arms adapted to receive a cushioning unit between them, and means integrally united to and connecting said arms at their rear ends, said means comprising a plurality of spaced webs one of which is adapted to engage said back-stop and one of which is adapted to engage said cushioning unit, and a plurality of parallel webs connecting said spaced webs and in transverse alignment with said arms. 85

2. A draft yoke adapted at its forward end to be connected to a car coupler and having a rear end adapted to engage a draft rigging back-stop, said yoke involving a pair of spaced arms adapted to receive a cushioning unit between them, and means integrally united to and connecting said arms at their rear ends, said means comprising a plurality of spaced webs one of which is adapted to engage said back-stop and one of which is adapted to engage said cushioning unit, a plurality of parallel spaced webs connecting said spaced webs, and a plurality of rearwardly divergent 100 webs connecting said spaced webs. 105

3. A draft yoke adapted at its forward end to be connected to a car coupler and having a rear end adapted to engage a draft rigging back-stop, said yoke involving a pair of spaced arms adapted to receive a cushioning unit between them, and means integrally united to and connecting said arms at their rear ends, said means comprising a plurality of spaced webs one of which is adapted to engage said back-stop and one of which is adapted to engage said cushioning unit, and a plurality of rearwardly divergent webs connecting said spaced webs. 110 115

4. A draft yoke involving a pair of spaced arms adapted at their forward ends to be connected to a car coupler, means integrally united to and connecting said arms at their rear ends, said means including spaced webs one of which is adapted to engage the backstop and the other of which is designed to engage the cushioning unit, and longitudinally extending ribs projecting outwardly from said arms and extending upon opposite 120 125 130

sides of the web engaging the cushioning unit.

5. A draft yoke involving a pair of spaced arms adapted to receive a cushioning unit between them and adapted at their forward ends to be connected to a car coupler, and means integrally united to and connecting said arms at their rear ends, said means comprising a plurality of spaced webs one 10 of which is adapted to engage a draft rigging back-stop and one of which is adapted to engage said cushioning unit, and said arms being provided with outwardly projecting ribs extending on opposite sides of the said web which is adapted to engage said cushioning unit.

6. A draft yoke involving a pair of arms adapted to receive a cushioning unit between them and adapted at their forward ends to be connected to a car coupler, and means integrally united to and connecting said arms at their rear ends, said means comprising a plurality of longitudinally spaced webs, one of which is adapted to en-

gage a backstop and the other of which is 25 designed to engage the cushioning unit each of said arms being provided for a portion of its length with an outwardly projecting rib extending forwardly substantially from one of said webs to a point in advance of 30 the foremost one of said webs.

7. A draft yoke involving a pair of arms adapted to receive a cushioning unit between them and adapted at their forward ends to be connected to a car coupler, and 35 means integrally united to and connecting said arms, said means comprising a plurality of spaced webs one of which is adapted to engage a draft rigging back-stop and one of which is adapted to engage a cushioning unit, said arms being extended to the rear of said cushioning unit engaging web in alignment with the adjacent portions of said arms in advance of said last named web.

In testimony whereof I affix my signature.

BYERS W. KADEL.
